US00D896084S

(12) **United States Design Patent** (10) **Patent No.:** **US D896,084 S**
(45) **Date of Patent:** **** Sep. 15, 2020**

(54) **ACTUATOR**

(71) Applicant: **S. C. Johnson & Son, Inc.**, Racine, WI (US)

(72) Inventors: **Ronald H. Spang, Jr.**, Kenosha, WI (US); **Richard M. Parysek**, Oak Creek, WI (US); **Steven A. Zach**, Waterford, WI (US); **Marilyn M. Johnson**, Wauwatosa, WI (US); **Imtiaz A. Musaliar**, Evanston, IL (US); **Neema Pourian**, Chicago, IL (US); **Jose L. Padilla**, Cicero, IL (US); **Katherine A. Reiser**, Mount Prospect, IL (US)

(73) Assignee: **S. C. Johnson & Son, Inc.**, Racine, WI (US)

(**) Term: **15 Years**

(21) Appl. No.: **29/727,541**

(22) Filed: **Mar. 11, 2020**

Related U.S. Application Data

(63) Continuation of application No. 29/661,390, filed on Aug. 27, 2018, now Pat. No. Des. 880,298.

CLAIM

The ornamental design for an actuator, as shown and described.

DESCRIPTION

FIG. 1 is an isometric view of a top, front, and right side of an actuator;

FIG. 2 is a front elevational view of the actuator of FIG. 1; FIG. 3 is a rear elevational view of the actuator of FIG. 1; FIG. 4 is a right side elevational view of the actuator of FIG. 1;

FIG. 5 is a left side elevational view of the actuator of FIG. 1; and,

FIG. 6 is a top plan view of the actuator of FIG. 1. The dash-dash-dash broken lines are included for the purpose of illustrating portions that form no part of the claimed design.

1 Claim, 6 Drawing Sheets
